PAIR OF PLIERS

Flora M. Mattingly, Glen Ellyn, Ill.

Application July 30, 1958, Serial No. 51,989

Term of patent 14 years

(Cl. D54—13)

Fig. 1.

Fig. 2.

Fig. 3.

Fig. 4.

Fig. 5.

Figure 1 is a front elevational view of a pair of pliers embodying the new design;

Figure 2 is a back elevational view similar to that of Figure 1;

Figure 3 is a side elevational view thereof;

Figure 4 is a plan view thereof; and

Figure 5 is a bottom view thereof.

The design for the pliers disclosed is characterized by the ornamentation as shown on the jaws.

I claim:

The ornamental design for a pair of pliers, as shown and described.
